WILLIAM E. EDWARDS, OF JOHNSON CITY, AND HARRY O. STALKER, OF BINGHAMTON,
NEW YORK.

SIZE AND STYLE STAMP FOR INSOLES AND OUTSOLES OF SHOES.

1,391,175.

Specification of Letters Patent. Patented Sept. 20, 1921.

Application filed September 17, 1920. Serial No. 410,909.

To all whom it may concern:

Be it known that we, WILLIAM E. EDWARDS and HARRY O. STALKER, citizens of the United States, residing at Johnson City and Binghamton, respectively, in the county of Broome and State of New York, have invented certain new and useful Improvements in Size and Style Stamps for Insoles and Outsoles of Shoes, of which the following is 10 a specification.

Our invention relates to improvements in size and style stamps for insoles and outsoles of shoes whereby the marks for classification of size and style for outsoles and in- 15 soles may be applied in the same operation, with the shaping or cutting of the sole, and it has for its object to provide a simple, neat, accurate, rapid and effective method of marking the soles for sorting and classifying. 20 With these objects in view, our invention consists of certain novel features of construction and arrangement of parts as will be hereinafter fully described and pointed out in the claims, reference being 25 had to the accompanying drawings, in which—

Figure 1 is a side view of our device in operation, as applied to the sole of a shoe;

Fig. 2 is an edge view of a part of our 30 device;

Fig. 3 is a top plan view of a part of our device;

Fig. 4 is an edge view of a part of our device;

Fig. 5 is a bottom plan view of a part of our 35 device;

Fig. 6 is an edge view partly in cross section of a part of our device; and

Fig. 7 is an edge view partly in cross sec- 40 tion of a part of our device.

The same reference characters denote like parts in each of the several figures of the drawings.

It is well understood that our device is 45 applied to the usually operative mechanism for shaping the soles of shoes. It is well understood that the present method of sorting and classifying outsoles and insoles after being shaped is laborious and cumbersome. 50 After they have been shaped to a pattern they have to be sorted according to style and size, and this is accomplished, in one way, by the operator dashing a mark of paint with a brush of some color over those

of one style and size, and then applying another color to those of another size and style and the sorting is accomplished by grouping those of the same color together. By our invention the outsoles and insoles are automatically marked in one operation with size 55 and style marks, while being shaped. In carrying out our invention, we make use of the usual pattern holding and cutting mechanism A which has the cutting knife b and the usual plunger rods ee connected with 60 the face plate 2 and also having the bed plate 3 for supporting and holding the usual pattern 4 which may be removably mounted on bedplate 3 in any convenient manner, and on the under side of face plate 2, we 65 removably mount in any convenient manner the pressure plate 5 which may be of the same general outline as the style pattern 4. Across the under face of plate 5 we inlet a cross channel or groove y having the in- 70 wardly beveled sides or edges 5' 5'; slidably mounted in the groove y we have the stamping plate 7 having on its outer surface the raised letters or figures 8, 8 indicating the size and style marks to be made on the upper 75 surface of the insole or outsole being cut. In our mechanism as stated, we make use of the usual mechanically operated cutting knife b adapted to move around the pattern 4; in the upper surface of pattern 4 we have 80 the channel or groove 9. In channel 9 we mount the stamping plate 10 having on its outer surface the raised letters or figures 11, 11, indicating the size and style marks to be made on the surface of the insole or 85 outsole being cut. On the pattern 4 we place the sole leather 6 to be cut and marked, which is held in position for cutting in any 90 convenient manner. The cutting knife b is moved around the pattern 4 in the usual 95 method of a sole shaping mechanism, and thus cuts the sole 6 in conformity to the outline of the pattern 4; at the same time the pressure of plate 5 upon the sole 6 causes the 100 marking letters 8, 8 to be impressed upon the upper surface of the sole 6; the pressure of the leather 6 on stamping plate 10 mounted in the surface of pattern 4 causes the letters or figures 11, 11 of stamp to be impressed in the under surface of the sole 6; 105 and in this manner the size and style marks may be impressed upon both sides of the sole, being cut or shaped from the pattern.

Or the stamp 7 may be removed from plate 5 and a new set of letters therein inserted to correspond with the letters or marks on another pattern, inserted for use. Or the 5 stamp 7 may be removed and an impression made only from stamp 10 in the surface of the pattern 4. Having thus marked the in-soles and outsoles when cut, they can be immediately sorted and grouped into their 10 proper classification preparatory to use.

Having thus described our invention, what we claim as new and for which we desire Letters Patent, is as follows:

1. In a size and style stamp for insoles and outsoles, in connection with an operative vertical plunger part, supporting and moving a face plate in alinement with a bed plate beneath the same, and adapted to receive the pressure of the face plate, a sole 15 pattern removably mounted on said bed plate, having a cross groove in the upper surface thereof, and a stamp having raised letters or figures in the upper face thereof mounted therein; a pressure plate mounted 20 on said face plate in alinement with the pattern, a cross groove in the lower face thereof

and means for vertical movement of the plunger and pressure plate.

2. In a size and style stamp for in-soles and out-soles, the combination with an operative vertical plunger supporting and moving a face plate in alinement with a bed plate beneath the same and adapted to receive the pressure of the face plate, a sole 30 pattern removably mounted on said bed plate, a stamp having raised marking means on the upper face thereof mounted on the sole pattern, said stamp indicating the style and size of the sole pattern, a pressure plate mounted on said face plate of the plunger 35 in alinement with the sole pattern and provided with a cross groove in the under face thereof, said groove adapted to receive stamps with different marking means thereon, and a stamp removably mounted in said 40 groove, the pressure plate adapted to be used with sole patterns of different size and to receive in the cross groove the proper 45 stamp to correspond with the sole pattern used.

WILLIAM E. EDWARDS.
HARRY O. STALKER.
